[57] CLAIM

The ornamental design for a wire twister tool, as shown and described.

DESCRIPTION

FIG. 1 is a top, right side perspective view of a wire twister tool showing my new design;

FIG. 2 is a bottom, left side perspective view thereof; FIG. 3 is an enlarged front elevational view thereof, shown fragmented for clarity of illustration;

FIG. 4 is an enlarged fragmentary left side elevational view of FIG. 1;

FIG. 5 is a bottom plan view of FIG. 1; and,

FIG. 6 is a top plan view of FIG. 1.

The broken line showing of a handle is for illustrative purposes only and forms no part of the claimed design.

FIG. 1

FIG. 2

FIG. 3

FIG. 3

FIG. 4
